UNITED STATES PATENT OFFICE

ALONZO W. RUFF, OF YORK, PENNSYLVANIA, ASSIGNOR TO YORK ICE MACHINERY CORPORATION, OF YORK, PENNSYLVANIA, A CORPORATION OF DELAWARE

REFRIGERATED DISPLAY CABINET

Application filed May 8, 1931. Serial No. 536,027.

The present invention relates to refrigerated display cabinets for the storage and display of frozen food products, and particularly to the circulation of cold air therein. Unless air is so circulated in the cabinet that a relatively high humidity is maintained adjacent the surfaces of the articles on display, there occurs drying out or desiccation of some classes of goods, particularly meats and fish.

10 The goods being frozen before they are placed in display cabinets, they give off no heat. The purpose of refrigeration by means of forced circulation of cold air is to take care of heat leakage from the exterior of the cabinet. It is desirable, therefore, that forced circulation of air in heat exchanging relation with an expansion or brine coil be employed, the air moving past the coil at a relatively high velocity to insure rapid heat exchange but at a more reduced velocity in those positions of the cabinet in which it is necessary to maintain stored goods at relatively low temperatures.

20 The difficulty usually experienced with forced circulation is that turbulence adjacent the surfaces of the goods in the cabinet reduces the humidity of the air immediately above the goods and causes the desiccation referred to.

30 In the present invention the cabinet comprises a casing, the upper portion of which is provided with display windows, and in which there are storage trays, storage drawers and the usual display tray, preferably inclined and visible from the front of the cabinet. A refrigerator coil is disposed within the casing, as is also a fan for effecting forced circulation of air in the cabinet, the fan being arranged in proximate relation to the coil

40 to provide for effective heat exchange between substantially all of the air and the coil.

The trays and drawers are each provided with side and end flanges so shaped and spaced from each other and from the walls of the cabinet that channels are formed to direct the moving air throughout the cabinet without causing turbulence at or near the goods in the various receptacles.

50 The invention will be more fully understood from the following description thereof

taken in connection with the accompanying drawings, in which:—

Fig. 1 is a vertical transverse section of the cabinet taken on line 1—1 of Fig. 2;

Fig. 2 is a longitudinal section of the cabinet taken on line 2—2 of Fig. 1; and

Fig. 3 is a perspective view of the cabinet shown in Figs. 1 and 2.

Referring to the drawings, the refrigerator cabinet comprises the usual insulated front and back walls 11, 12, side walls 13, 14 and base 15. The upper portion of the cabinet has an inclined front 16 consisting of one or more glassed panels 17 for display purposes. Glassed doors 18 at the rear upper portion of the cabinet provide for access to the trays within the cabinet. The top 19 of the cabinet contains suitable lamps 21 separated from the articles within the refrigerator by two or more spaced glass panels 22 whereby the interior of the cabinet is illuminated, but is insulated from the heat given off by the lamps. A metal cover 20 extends longitudinally of the cabinet top and over the lamps.

75 In the rear wall of the refrigerator are doors 23 which may be opened to withdraw storage drawers 24. As will be seen in Fig. 1, these drawers are arranged in superposed relation and provided with rollers 25 adapted 80 to ride on tracks 26. Rollers 27 are supported in brackets at the end of the track adjacent the doors 23 so that the drawers may be withdrawn with little effort even when full. The drawers are also separated from each other 85 in a horizontal plane, as shown in Fig. 2, to permit circulation of cold air throughout the cabinet.

90 Each drawer 24 is provided with a flange and the rear wall frame is faced with suitable packing 29 adjacent the drawer openings with which the drawer flanges cooperate to minimize leakage when doors 23 are opened.

95 Disposed centrally of the cabinet is a circulating fan 31 driven by an electric motor 32. Connections to a source of current for the motor and lamps may be made by means of sockets 33, and switches 34 are provided for controlling the motor and lamp circuits. 100

Supported on brackets 35 above drawers 24 is a tray or compartment 36 having a rear wall 37, spaced from the rear wall of the cabinet to form a passage 38, and an inclined 5 front wall 39. The upper end 41 of the front wall terminates some distance below top 19, and as shown in Fig. 1, is vertical. The lower portion of the wall is inclined downwardly and rearwardly, as shown at 42. Disposed forwardly of compartment 36 is a display tray 43 having a contour such that the tray is parallel to and spaced from the front wall of the rear compartment, thus forming a passage 44 between the two trays. It will 10 be seen that the bottom 45 of tray 43 is supported on the sill of the display panel and is closed to the interior of the cabinet. The bottoms, sides and ends of all of the drawers and trays are imperforate, only the top being 15 open for access thereto.

The top edge of tray 43 is spaced from the top of the cabinet, being at about the same height as the top of wall 41. In order to prevent more than a limited amount of cold 20 air from circulating above the goods in the display tray, a curtain 46 of some suitable flexible material is hung from the top of the cabinet. The curtain acts as a baffle against 25 the entrance of air to the tray, but may flap 30 back and forth with respect to the top edge of the tray a distance sufficient to permit a limited quantity of air to enter and leave the space above the goods in the tray. Turbulence in the display compartment is thus sub- 35 stantially eliminated.

Adjacent and parallel to the front wall of the cabinet is a refrigerating coil 47 through which brine or other suitable refrigerating medium is circulated. Interposed between 40 the refrigerating coil and drawers 24 is a plate 48 extending longitudinally the full length of the cabinet and from the cabinet base nearly to the bottom of tray 36. The refrigerating coil substantially fills the com- 45 partment thus formed by the front wall of the cabinet and plate 48, insuring a high velocity of air therethrough, and rapid heat transfer between the coil and air.

A long slot-like passage 49 is provided be- 50 tween the upper edge of plate 48 and the forward bottom corner of tray 36 through which relatively warm air is drawn to be cooled by coil 47. Plate 48 is provided with an aperture intermediate its ends, which aperture corresponds in area and shape with the fan casing 51. The fan casing is open at each end, forming a conduit through which the fan draws cold air and forces it rearwardly 55 into the lower central portion of the refrigerator from which it flows laterally and upwardly around all of the drawers and between the trays before being returned to the brine coil compartment. Warm air which 60 has leaked into the cabinet is thus effectively 65

removed from the spaces between the drawers and trays.

In Fig. 1 the direction of the air currents is indicated by arrows. It is to be particularly noted that air in the storage compartment 36 70 and in display tray 43 is effectively pocketed and that there is little or no turbulence of air in the trays. The same is true of the air within the storage drawers, the corners and 75 seams of which are air-tight. The sides and bottoms of the trays and drawers are, however, continuously cooled by the circulated air. The relatively long slot-like passages 38, 44 and 49 provide for equal distribution of cold air and withdrawal of warm air so that 80 substantially uniform circulation of air throughout the cabinet is insured.

It will be apparent that the construction and arrangement of the circulating and refrigerating apparatus described will effectively 85 maintain low temperatures in and around the storage drawers and trays. While the fan is capable of circulating a relatively large volume of air, it is so distributed through the slot-like channels formed by the 90 walls of the drawers and trays that large outlets are provided. In this manner the turbulence usually present in forced circulating systems is practically eliminated. Tests have demonstrated, for instance, that the temperature in the space immediately under the 95 top of the cabinet may be 25° higher than that around the drawers, and that this temperature difference is substantially constant.

While the particular relation and shape of 100 the drawers and trays as shown are preferred, the invention is susceptible of application to modified forms of the several receptacles employed in the cabinet. It is, therefore, to be understood that the drawings are 105 merely illustrative of one form of the invention.

What is claimed is:—

1. In a refrigerated display cabinet, a longitudinal vertical partition therein, said partition being spaced from the front wall of the cabinet and terminating below the top thereof; a heat exchange element substantially filling the space between said front wall and said partition; and a fan for circulating air 110 downwardly through said space and into the rear portion of the cabinet.

2. In a refrigerated display cabinet, a longitudinal vertical partition therein, said partition being spaced from the front wall of the cabinet and terminating below the top thereof; a display tray disposed adjacent the front of said cabinet; a storage tray disposed rearwardly of said display tray and above said partition, said storage tray being spaced 120 from the rear wall of said cabinet and from said display tray; a heat exchange element substantially filling the space between said front wall and said partition; and a fan for circulating air downwardly through said 125

130

space and into the rear portion of the cabinet.

3. In a refrigerated display cabinet, a longitudinal vertical partition therein, said partition being spaced from the front wall of the cabinet and terminating below the top thereof; a plurality of storage receptacles in the rear of said partition, said receptacles being spaced from each other and having imperforate bottoms and sides; a heat exchange element substantially filling the space between said front wall and said partition; and a fan for circulating air downwardly through said space and upwardly around said receptacles.

15 4. In a refrigerated display cabinet, a longitudinal vertical partition therein, said partition being spaced from the front wall of the cabinet and terminating below the top thereof; a plurality of storage receptacles disposed between said partition and the rear wall of said cabinet, said receptacles being spaced from each other; a display tray disposed in the upper forward portion of said cabinet; a storage tray disposed in the upper portion of said cabinet, said storage tray being spaced from said partition, said display tray, said receptacles and the rear wall of the cabinet; a heat exchange element substantially filling the space between said partition and the front wall of the cabinet; and a fan for circulating air downwardly around said element and through the spaces between said receptacles and said trays.

35 5. In a refrigerated display cabinet, a longitudinal vertical partition therein, said partition being spaced from the front wall of the cabinet and terminating below the top thereof; a display tray disposed adjacent the front wall of said cabinet, said tray being inclined upwardly and rearwardly and terminating below the top of the cabinet; a flexible baffle depending from the top of the cabinet, said baffle having a free lower edge extending to and parallel with the top edge of the display tray; a heat exchange element substantially filling the space between said front wall and said partition; and a fan for circulating air downwardly through said space and into the rear portion of the cabinet.

50 50. In testimony whereof I have signed my name to this specification.

ALONZO W. RUFF.
